UNITED STATES PATENT OFFICE.

ANDERSON FULLER, OF AMSTERDAM, NEW YORK.

FOLDING STEP FOR RAILWAY-CARS.

No. 877,708.

Specification of Letters Patent.

Patented Jan. 28, 1908.

Application filed April 19, 1907. Serial No. 369,071.

To all whom it may concern:

Be it known that I, ANDERSON FULLER, a citizen of the United States, residing at Amsterdam, county of Montgomery, and State of New York, have invented certain new and useful Improvements in Folding Steps for Railway-Cars, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a bottom plan view of one end of a railway car showing my invention applied thereto. Fig. 2 is a view in end elevation of the same end of the car. Fig. 3 is a vertical cross-section of the same taken on the broken line 3—3 in Fig. 1. Fig. 4 is a vertical cross-section taken on the broken line 4—4 in Fig. 1. Fig. 5 is an enlarged detail showing the manner in which the notched portion of the handle slide-bar interlocks with a slideway-cleat.

The principal object of the invention is to automatically fold a temporary car-step, upon the starting of the car.

Other objects of the invention will appear in connection with the following description.

Referring to the drawings wherein the invention is shown in preferred form, 1, represents the floor or platform of a railway-car, mounted upon a truck, 2, partly shown in Fig. 1. The truck comprises in part the axle, 3, and car-wheel 4. The car is provided with the usual permanent steps 5.

Mounted upon the underside of the lower step, in bearings, 6, is a rock-shaft, 7, upon which are fixed two Z-shaped rocker arms, 8, forming supports for the temporary step, 9, which is adapted to swing from the extended position shown by solid lines in Figs. 1 and 2, to the folded position shown by dotted lines in Fig. 2, in which folded position the temporary step, 9, lies beneath the upper permanent step 5.

As a means for operating the temporary step, the rock-shaft, 7, is provided on one end with a segmental-gear, 10, adapted to be engaged by a toothed rack, 11, on the lower end of a slide-bar, 12, vertically movable in slide-

ways formed in the cleats, 13, on the outer side of the string-board, 14, of the permanent steps, and provided with a handle 15.

The slide-bar, 12, is provided on one of its vertical edges with a notched portion, 16, adapted to receive and interlock with the upper slideway-cleat, 13, when the bar is in its lowered position, as shown in Fig. 2, and it is also provided with a notched portion, 17, adapted to receive and interlock with the same slideway-cleat when the slide-bar is in its raised position.

A spring, 20, yieldingly forces the slide-bar toward the portion of the slideway-cleat adapted to enter said notches, so that the bar automatically locks itself in either the raised or lowered position, but can be released by forcing the bar, by hand or otherwise, to the left, as seen in Fig. 2, against the force of the spring, 20, thus permitting the bar to be raised and lowered when desired.

Normally the temporary step, 9, is supported in folded position with the slide-bar, 12, locked in raised position by the engagement of its notched portion, 17, with the upper slideway-cleat, 13, and when it is desired to use the temporary step, as when the car stops for passengers to enter or leave the car, the slide-bar is disengaged from the upper slideway-cleat and forced downwardly by hand until the temporary step has been swung to the position shown in Fig. 2, in which position it is securely held by the engagement of the notched portion, 16, of the slide-bar, with the upper slideway-cleat.

The temporary step can be folded by hand if desired, by disengaging the slide-bar from the upper slideway-cleat, and then raising the bar from the position shown in Fig. 2, to that shown in Fig. 3, in which position it is supported by the engagement of its notched portion, 17, with the upper slideway-cleat.

An important feature of my invention consists in means whereby, when the car is started, the temporary step will be automatically moved from extended to folded position. To accomplish this, I connect the lower end of the slide-bar, 12, by means of a cord, 21, passing over suitable pulleys, with a drum, 22, loosely mounted on the axle, 3, and provided with a clutch member, 24, adapted at certain times to be forced into engagement with a clutch member, 25, fixed upon the axle, 3, whereby, when the clutch members are in engagement with each other with the car in motion, the cord, 21, will be

wound upon the drum 22. The clutch member and drum, 22, are capable of sliding movements longitudinally of the axle, 3, and are adapted to be slid along the axle to cause engagement and disengagement of the clutch members with each other, by means of a forked arm, 26, engaging a flange, 27, on the drum, said forked arm being fixed upon a rock-shaft 28, supported in hangers, 29, depending from the underside of the car floor, said shaft, 28, extending longitudinally of the car. Projecting from the rock-shaft, 28, at a point opposite the temporary step, is a rocker arm, 30, which extends into the path traversed by the temporary step in swinging from its extended position to its folded position. The various parts are so located and proportioned that when the temporary step, 9, is folded, it engages and supports the rocker arm, 30, as indicated by dotted lines in Fig. 2, thereby holding the clutch member, 24, out of engagement with the clutch member, 25; and, when the temporary step is swung from the folded position to the extended position, the rocker arm, 30, by its own weight, serves to rock the shaft, 28, and thereby through the rocker arm, 26, force the clutch member, 24, into engagement with the clutch member 25.

30 The cord, 21, passes from the lower end of the slide-bar, 12, around a small pulley, 31, on the lower slideway-cleat; thence around pulley, 32, fixed upon the lower arm of a lever, 33, fulcrumed intermediately of its ends upon the string-piece, 14, the upper end of which lever is provided with a friction roller, 34, engageable with the slide-bar, whereby, when a pull is exerted upon the cord, 21, the upper end of the lever, 33, with its roller, 34, is forced against the notched edge of the slide-bar, 12, moving said bar to the left, as shown in Fig. 2, against the force of the spring, 20, and thereby disengaging the notched portion, 16, from the upper slideway-cleat. The slide-bar is thus held disengaged from the slideway-cleat, 13, and free to respond to the upward pull of the cord, 21, as long as such a pull is exerted upon said cord.

50 The step being in the extended position shown in Fig. 2, with the clutch members, 24 and 25, in engagement with each other, when the car is started, the drum, 22, will be rotated and the cord, 21, wound thereupon, the pull of said cord releasing the slide-bar, 12, and drawing the same upward as above described, until the temporary step has been swung from the extended position to the folded position. As the temporary step approaches the folded position, it engages the rocker arm, 30, forcing the same upwardly until it thereby causes the disengagement of the clutch member, 24, from the clutch member, 25, at substantially the same time that the step reaches its folded

position, in which folded position it is automatically locked by the engagement of the notched portion, 17, of the slide-bar, 12, with the upper slideway-cleat, as soon as the pull upon the cord, 21, is relieved.

In order to provide sufficient slack for the cord, to permit the step to be lowered by hand in case the cord on the drum should not be unwound after the step has been automatically folded, and before it is desired to extend the step again, I run the cord, 21, from the pulley, 32, to a pulley, 36, on the string-piece, 14, then to a pulley, 37, on the underside of the car floor, then to a pulley, 38, on the remote end of a lever, 39, fulcrumed at, 40, upon the underside of the car floor, and normally held by the coil spring, 41, against a stop, 42, in a position extending longitudinally of the car, the cord passing from the pulley, 38, to a pulley, 43, on the other end of said lever, then to a pulley, 44, on the underside of the car body, whence it passes to the drum 22. The pulleys, 37 and 44, lie on opposite sides of the lever, 39, so that a pull upon the cord, 21, causes the lever, 39, to be swung approximately into line with the two pulleys, 37 and 44, as indicated by dotted lines in Fig. 1. Whenever the clutch members are disengaged from each other, the lever, 39, will automatically assume the position shown in Fig. 1; and, if the clutch members should be brought into engagement with each other before the temporary step has been fully lowered, the pulley, 39, will yield to the pull of the cord, 21, and let out enough of the cord to permit the step to be fully extended. The coil spring, 41, is preferably coiled around the pivot-bolt or pin, of the lever, 39, having one end fixed to said bolt, and the other end to the lever.

What I claim as new and desire to secure by Letters Patent is

1. In a car, the combination with a permanent step, a folding step and means for extending the folding step, of the car-axle, connections between the folding step and car-axle whereby the folding step is automatically folded by movement of the car and step - actuated mechanism for interrupting the connection between the folding step and car-axle when said step reaches folded position.

2. In a car, the combination with a permanent step, a folding step and means for extending the folding step, of the car-axle, connections between the folding step and car-axle whereby the folding step is automatically folded by movement of the car, and means for automatically disconnecting the step - operating mechanism from the axle when said step reaches folded position.

3. In a car, the combination with a permanent step, a folding step and means for extending the folding step, of the car-axle, a

drum and clutch member together loosely mounted on said axle and capable of slide movements longitudinally thereon, a clutch member fixed to said axle in the path of said other clutch member, a cord connecting the folding-step-operating mechanism with said drum, guides for said cord, and clutch-shifting mechanism having a member projecting into the path of the operating step and adapted to be operated thereby.

4. In a car, the combination with a permanent step, a folding step and means for extending the folding step, of the car-axle, a

drum loosely mounted on the car-axle, means whereby the drum is at certain times connected with, and at certain other times disconnected from, the axle, a cord connecting the folding step-operating mechanism with said drum, guides for said cord, and a yielding take-up for said cord.

In testimony whereof, I have hereunto set my hand this 15 day of April, 1907.

ANDERSON FULLER.
